COMBINED HOLDER AND OPENER FOR SAFETY PINS

William H. Drake, Carpenteria, Calif.

Application March 12, 1956, Serial No. 40,571

Term of patent 14 years

(Cl. D86—10)

The single figure is a perspective view substantially from the side of the combined holder and opener for safety pins, showing the new design.

The device is symmetrical side for side, consequently the side opposite that shown is substantially similar to it.

I claim:

The ornamental design for a combined holder and opener for safety pins, as shown and described.
